UNITED STATES PATENT OFFICE

157,061

SPECTACLE FRAME

Frank W. Lindblom, Warwick, R. I., assignor to
Welsh Manufacturing Company, a corporation
of Rhode Island

Application July 30, 1949, Serial No. 4,221

Term of patent 3½ years

(Cl. D57—1)

To all whom it may concern:

Be it known that I, Frank W. Lindblom, a citizen of the United States of America, residing at Warwick, county of Kent, State of Rhode Island, have invented a new, original, and ornamental Design for a Spectacle Frame, of which the following is a specification, reference being had to the accompanying drawing, forming a part thereof.

Fig. 1 is a front elevational view of a spectacle frame; and

Fig. 2 is a top plan view thereof with the temples in a folded condition showing my new design.

The dominant part of the design is shown in full lines.

I claim:

The ornamental design for a spectacle frame, substantially as shown and described.

FRANK W. LINDBLOM.
